UNITED STATES PATENT OFFICE.

GEORGE HALL CLARK, OF CAMBRIDGE, MASSACHUSETTS, ASSIGNOR TO CROSBY STEAM GAGE & VALVE COMPANY, OF BOSTON, MASSACHUSETTS, A CORPORATION OF MASSACHUSETTS.

SAFETY-VALVE.

1,356,853.

Specification of Letters Patent. Patented Oct. 26, 1920.

Application filed October 23, 1919. Serial No. 332,749.

To all whom it may concern:

Be it known that I, GEORGE HALL CLARK, a citizen of the United States of America, and resident of Cambridge, in the county of Middlesex and State of Massachusetts, have invented new and useful Improvements in Safety-Valves, of which the following is a specification.

My invention relates to safety valves for steam boilers, and consists in improvements applicable to safety valves of the prevalent huddling chamber type, such as the commercially known Crosby standard stationary valve. The object of my invention is to increase the maximum lift of such a valve, without sensibly affecting the behavior of the valve at low values of lift, either when opening or closing.

In the drawings hereto annexed which illustrate my invention and show an example thereof,—

Figure 1 is a vertical cross section of a safety valve showing its well known characteristic parts; and

Fig. 2 is a fragmentary side elevation of that portion of the valve structure which contains the member chiefly characteristic of my improvement.

In the drawing the following named parts are comprised in a safety valve of the general character indicated: A is the valve disk, B the base on which is formed valve seat S. The valve disk and base are shaped to form the annular pressure chamber or huddling chamber D which lies between the seat S and the lip a. The flange K provided with a series of apertures F terminates in a lip f between which and the lip a is located the lip aperture E, which is slightly open when the disk A is seated at S. The adjusting ring C is adjustably mounted on the base B immediately below the flange K and cooperates in the well known manner with the apertures F to control the blowdown of the valve.

The well-known action of safety valves of this type is as follows: When pressure in the boiler reaches the point at which the valve is set, the disk A lifts slightly, steam passes through the seat aperture thus produced into the chamber D from which there are two outlets, one through the lip aperture

E and the other downwardly, through the holes F and then outward over the ring C.

The aggregate of the areas of the lip aperture E and that over the ring C is such that pressure is built up in the chamber D and the valve pops, receiving a sudden, relatively large increase in lift. The extent of this lift depends on the total upward pressure on the disk including the area in the chamber D and the downward force exerted by the spring. Assuming the valve to be blowing freely and to be of sufficient size to reduce the boiler pressure gradually, the equilibrium is disturbed as pressure is reduced and the lift decreases. The discharge area at the seat S which may be termed the seat vent is directly proportional to the lift, while the discharge area from the chamber D is the aggregate of the area of openings from the chamber D when the valve is closed and the increment in area brought about by each increase in lift.

As the lip diameter is greater than the seat diameter the total effective area at the lip increases faster per unit of lift than the total area at the seat. In short, the lip vent is initially larger than and increases faster than the seat vent. As the valve disk approaches its seat the outside area or lip vent is very large as compared with the area of the seat vent, and this results in a sudden closing of the valve. If x and y represent respectively the vent areas at seat and lip, it is clear that as the valve approaches its seat the ratio $\frac{x}{y}$ is decreasing very rapidly. This

ratio $\frac{x}{y}$ is the factor which determines the pressure in the chamber D and the consequent lifting force on the disk. For this reason I provide means to make this factor or ratio approach more nearly to unity at the higher lifts so that the valve may experience consequently an increase in lift and capacity. But it must be borne in mind that conditions at the lower lifts must be left undisturbed so that the designed factors for controlling the valve at those values of lift may not be appreciably altered.

In order to obtain increased lifts at the higher values of pressure without disturbing conditions at the lower values, I pro-

vide means by which in effect the outlet area at the lip or lip vent is made to approximate progressively to equality to the outlet area at the seat, leaving the controlling conditions unchanged at low lifts.

Returning now to the drawing: I attach to or form integrally with the adjusting ring C an annular screen G which lies around the valve disk adjacent to the lip vent. This 10 screen is perforated with a number of circular apertures H which are so proportioned and positioned that at low lifts there is ample passage for steam escaping from the lip vent at E; that is to say, at low lifts substantially 15 none of the solid screen material is opposed to the free discharge of steam. But as the disk A lifts higher and the disk lift *a* rises, it comes into opposition to greater and greater extent with the solid 20 material of which the screen G is composed; or speaking conversely, the width of the apertures H measured along horizontal chords becomes less and less.

This progressive opposition of more and 25 more screen area to the discharge of the steam as the valve lifts, obstructs the efflux of steam, and has substantially the same effect as would be produced by an actual constriction of the vent area E. This results 30 in effect in making the area ratio $\frac{x}{y}$ approach unity at the higher lifts. Relatively to the lip vent the area of the series of holes H decreases progressively as the lift increases, but this area is sufficiently large and 35 is so disposed with reference to the lip as to disturb conditions very slightly, if at all, at low lifts. Also, the aggregate area of the holes H should be so proportioned as always to exceed the seat vent area by a considerable margin.

The result of employment of this improvement is to increase the maximum lift of a valve from its original value by from fifty 40 to seventy-five per cent.

I claim:

1. In a safety valve of the character described, the combination of a valve disk and a base arranged to provide a lip-vent be-

tween them, and means to obstruct the lip-vent at relatively high valve-lift positions. 50

2. In a safety valve of the character described, the combination of a valve disk and a base arranged to provide a lip-vent between them, and means to obstruct progressively the lip-vent at relatively high valve-lift positions. 55

3. In a safety valve of the character described, the combination of a valve disk and a base arranged to provide a lip-vent between them, and a screen adjacent to the lip-vent and disposed to obstruct the same at relatively high valve-lift positions. 60

4. In a safety valve of the character described, the combination of a valve disk and a base arranged to provide a lip-vent between them, and a screen adjacent to the lip-vent and disposed to obstruct the same at relatively high valve-lift positions. 65

5. In a safety valve of the character described, the combination of a valve disk and a base arranged to provide a lip-vent between them, an adjusting ring, and a screen carried on the ring, adjacent to the lip-vent and disposed to obstruct the same at relatively high valve-lift positions. 70

6. In a safety valve of the character described, the combination of a valve disk and a base arranged to provide a lip-vent between them, an adjusting ring, and a screen carried on the ring, adjacent to the lip-vent and disposed to obstruct the same progressively at relatively high valve-lift positions. 80

7. In a safety valve of the character described, the combination of a valve disk and a base arranged to provide a lip-vent between them, an adjusting ring, and an apertured screen carried on the ring, adjacent to the lip vent and disposed to obstruct the same at relatively high lift positions, the free area of the screen apertures being in the aggregate greater than the seat vent area at the maximum of the latter. 85

Signed by me at Boston, Massachusetts, 90 this 21st day of October, 1919.

GEORGE HALL CLARK
